QUICK-ACTING VISE HAVING ROCKABLE LEVER FOR SEQUENTIALLY POSITIONING AND ADVANCING SLIDABLE JAW

Burton H. Parker, Detroit, Mich.

Application August 14, 1947, Serial No. 768,683

6 Claims. (Cl. 81—26)

1

This invention relates to vise structures and more particularly to an improved quick action vise.

An important object of this invention is to provide an improved vise having a slidable movable jaw member which requires only a short operating movement of a single control member for clamping the movable jaw against further movement and for exerting an extremely high gripping pressure upon an object inserted between the jaws of the vise. Another important object of the invention is to provide an improved vise of this character which is quick acting in operation and obtains an extremely high gripping pressure with a minimum of effort. A further important object of this invention is to provide a vise of this character comprising few parts of relatively simple manufacture which are rugged in construction and are easily assembled for use and easily disassembled for inspection or replacement of parts. A still further object of the invention is to provide a vise of this character having the parts so located with respect to one another and the jaws that a clearance for working operations is provided on all sides of an object gripped by the jaws.

In carrying out the invention, the vise is composed of two jaw members, one of which is slidably movable toward and away from the other for initially gripping an object therebetween. An important feature of the invention relates to the relation of the fixed and movable jaw members and particularly to the novel sub-division of the movable jaw member into two relatively movable parts, one of which is slidably adjustable to initially engage and hold an object between the jaws, and the other part of which is subsequently capable of advancement in parallel relationship toward the fixed jaw to tightly grip an object therebetween. Another important feature of the invention is the provision of a novel lever member and a control therefor consisting of a single rotatable member which when operated in one direction will first securely clamp the slidable jaw structure against further movement and thereafter advance the object gripping part of the jaw structure into tightly compressed engagement with the object held between the jaws.

Various other objects, advantages and meritorious features of the invention will become more fully apparent from the following specification, appended claims and accompanying drawings wherein:

Fig. 1 is a side elevation of an embodiment of the present invention, partly broken away in sec-

2

tion, and showing the parts thereof in non-clamping position.

Fig. 2 is a side elevation of the vise similar to Fig. 1, partly broken away in section, and illustrating the parts thereof in clamping or gripping position.

Fig. 3 is a vertical sectional view of the vise taken along line 3—3 of Fig. 1.

Fig. 4 is a side elevation of the vise structure, 10 showing the vise proper turned 90° to its support in over-hanging relation to the side of a bench,

Fig. 5 is a top plan view of the vise structure in smaller scale, illustrating by full and dotted lines the swiveling movement of the vise on its 15 support.

Fig. 6 is a detail vertical sectional view taken along line 6—6 of Fig. 1, and

Fig. 7 is a top plan view of the movable jaw member taken along line 7—7 of Fig. 1, but omitting a dirt excluding cover plate.

In the present embodiment of the invention, a bench vise is shown but it is understood that the features of the invention may be incorporated into vises for use on milling machines, drill presses 25 and other types of apparatus.

Referring to Fig. 1, the vise is shown mounted on a table top or bench 10, adjacent to one edge thereof. A base plate 12 forming part of the vise structure is secured to the upper surface 30 of the bench by bolts 14 so that one side of the plate projects beyond the edge of the bench as shown in Figs. 1, 2 and 4. The base plate 12 may be of a generally circular formation as shown in Fig. 5 but cut away on the projecting side thereof to form notches having abrupt end walls 16 which will serve as stops as will be described more particularly hereinafter.

The projecting side of the base plate 12 is provided with a circular aperture 18. Surmounting 40 the base plate is an upwardly opening channel member 20 having a depending cylindrical projection or bearing 22 which removably fits the aperture 18 and projects therebelow as shown in Figs. 1 and 3. The channel member may be 45 clamped to the base in any suitable manner, such as by the provision of a cup-shaped clamping member 24 enclosing the lower projecting end of the bearing 22 and the further provision of a threaded stud member 26 which is threadedly engaged in a downwardly opening axial bore 28 in the cylindrical bearing 22. The stud member is shouldered at 30 to form a seat for the cup-shaped member. A handle 32, which is transversely slidable through the lower end of the stud member 26, will upon rotation in one direction

threadedly draw up the stud member and carry the cup-shaped member 24 into clamping engagement with the underside of the plate 12 to securely hold the channel member in adjusted position on the base plate. When the clamping engagement of the cup-shaped member is released, the channel member may be rotated or swiveled on the base plate about the axis of the bearing 22. The full and dotted line positions of the parts in Fig. 5 illustrate this swiveling movement.

The vise proper comprises a normally fixed jaw member 34 and a slidably movable jaw member 36. The jaws are supported in a novel manner by the channel member 20 for both rotation about a vertical axis and pivotal swinging movement about a horizontal axis. The fixed jaw 34 is integrally connected to an elongated solid supporting member or body 38 which extends at right angles to the jaw and is of a size to be removably received within and closely fit the upwardly opening channel of the supporting member 20 as shown in Fig. 3. Both the jaw 34 and its supporting body 38 may be cast in one piece as shown or separately formed and secured together.

The sliding jaw 36 is mounted on the body member 38 for longitudinal translational movement toward and away from the jaw 34. This is preferably accomplished by shaping corresponding longitudinally extending grooves 40-40 on the opposite sides of the body 38 and shaping the bottom side of the jaw 36 so that it slidably engages the upper surface 41 of the body 38 and partially embraces the top of the same. The depending sides of the movable jaw member 36 are provided with inwardly turned flanges 42-42 which enter the grooves 40-40 as shown in Fig. 3 and slidably fit the same to prevent lateral movement of the jaw member relatively to the body 38.

As previously mentioned, the elongated body 38 is swingably received within the channel member 20 and may be withdrawn therefrom when desired. Projecting through one side of the channel member 20 is a pivot pin 44 which projects through the supporting member and into the opposite side wall of the channel member. The supporting member is bored transversely to slidably receive this pin. One end of the pin 44 is provided with a projecting head 46 through which a transversely slidable handle 48 passes. The opposite end of the pin is threaded into the opposite side wall of the channel member 20 for detachable securing thereto. When mounted in place, the pin 44 serves as a horizontal pivotal axis about which the supporting member 38 may swing as shown by a comparison of Figs. 1 and 4. The pivot pin 44 may be withdrawn to allow the body 38 and associated parts to be removed as a unit from the base support.

Normally when the jaw members 34 and 36 are in the upright conventional position shown in Fig. 1 the supporting body 38 is locked in position in the channel member 20. This is preferably accomplished by providing a headed pin 50 shown in Fig. 3 having a reduced externally threaded shank 52 which is adapted to be threadedly engaged in a transverse bore formed in the body 38. The pin projects through one side of the channel member 20 and is provided with a transversely slidable handle 54 for exerting a turning force on the pin. The side wall of the channel member 20 is provided with an upwardly opening slot 56 through which the shank of the

pin extends, which is slightly curved as shown in Fig. 1 about the axis of the pivot pin 44. It is obvious that when the pin 50 is rotated in the direction for threaded advancement into the body 38, the shoulder formed by the head of the pin will engage the side wall of the channel member and frictionally lock the body 38 against pivotal swinging movement. However, when the pin 50 is backed off sufficiently to release the frictional compression, the body 38 may be swung about the pivot pin 44 carrying the clamping pin 50 therewith upwardly through the slot 56.

As a result of the structure thus far described it is possible to swivel the channel member 20 about the vertical axis of the bearing 22 to various positions such as those illustrated in Fig. 5. It is also possible to swing the two jaw members and their support 38 about a horizontal axis formed by the pivot pin 44 from the conventional position shown in Fig. 1 to a position 90° thereto shown in Fig. 4. This last position will dispose the jaws 34 and 36 in superimposed position which is highly convenient for certain operations performed on objects gripped between the jaw members. To accomplish this pivotal swinging movement the channel member 20 and the two jaw members 34 and 36 are rotated about the axis of the bearing 22 approximately 180° from the position shown in Fig. 1 so that the after end of the supporting body 38 projects from the bench. Thereafter, upon releasing the clamping pressure of the pin 50, the body 38 and the two jaws may be swung in a vertical plane to the position shown in Fig. 4. This will dispose the jaw 34 above the jaw 36 and by virtue of the fact that there are no protruding parts on the jaw 34 it is possible for the operator to clearly see the work being performed on an article gripped between the jaws. In the vertical position of the parts shown in Fig. 4, the body 38 extends closely by the notched edge of the base plate 12 and is swingable about the vertical axis formed by the bearing 22. The bearing axis is eccentrically disposed with respect to the center of the base plate and located relatively close to the notched edge thereof. When the body 38 is swivelled about the bearing axis it enters the notches and its extent of swivelling movement in either direction is limited by engagement with the abrupt end walls 16-16 of the notches.

The two jaw members 34 and 36 are preferably provided with removable gripping face plates which engage and grip the work. A face plate 58 having a serrated working surface is shown mounted on the fixed jaw 34. A face plate 60 is shown mounted on the movable jaw member 36 in opposed relation to the face plate 58. The face plate 60 is directly connected by screws 62 to a longitudinal movable part or member 64 of the structure of the jaw member 36.

The jaw member 36 is actually composed of two parts, the larger part 64 which is slidably movable on the body 38 and a smaller part 66 which is slidably movable on the upper end of the main part. Referring to Fig. 3, the upper end of the jaw member 36 is reduced in width to provide slide 66 which is under-cut on the opposite sides thereof as indicated at 68-68 to provide two parallel extending grooves. The smaller part 64 of the jaw member is shaped to embrace the slide 66 and is provided with inturned flanges 70-70 which enter the grooves 68-68 to form a sliding fit. Thus mounted, the part 64 is capable of longitudinal movement parallel to the move-

ment of the main part 36 toward and away from the opposing face plate 58 of the fixed jaw.

The forward end of the movable part 64 of the jaw structure is widened so as to project beyond the opposite sides of the larger part 36 of the jaw structure as shown in Figs. 4 and 7 and shaped so that the projecting sides of the part depend in overlapping relation to the sides of the main part. The projecting side portions of the part 64 beyond the sides of the jaw member 36 are each provided with an inclined face 72 as best shown in Figs. 2 and 4. The slide 66 of the jaw member 36 is provided with a rearwardly opening longitudinal slot 74 in which is received a coiled spring 76. As shown in Fig. 1, the forward end of the slot terminates in a circular recess forming a seat for the forward end of the spring. The rear end of the spring is seated upon a removable stop member 77 in the form of a vertical set-screw. The latter is threaded in a vertical hole opening out through the top and bottom of the rear end section of the part 64 and as is evident from Fig. 1 is retractable therefrom. In the position of the parts in Fig. 1 the coiled spring is under compression and exerts force against the step 77 urging the part 64 rearwardly of the main body portion 36. The upper surface of the jaw 36 may be protected by a removable cover plate 78 which is secured by the screw member 79. The cover plate overlies the hole through which the screw member 77 extends to protect these parts of the mechanism from dirt and other foreign material.

The movable jaw 36 is mounted on the body 38 in a novel manner such that upon operation of a single control member it may be positively clamped to the body 38 and also tightly grip an object interposed between the face plates 58 and 60. The novel means accomplishing this action comprises a rack in the form of an elongated toothed plate 80 mounted in the upper surface of the body 38 and secured thereto by screw members 82 at spaced intervals therealong. The teeth of the rack incline forwardly as shown in Figs. 1 and 2. The rack plate 80 has a transverse dimension less than the upper surface 41 of the body 38 as shown in Fig. 3 and is mounted centrally thereon. The bottom side of the jaw member 36 is shaped with a longitudinal groove 84 which accommodates the rack plate and has sufficient clearance thereabove so as to allow the jaw 36 to slide freely thereover.

Mounted on the jaw member 36 is a novel lever member 86 which is forked or bifurcated at its forward end to embrace the upper portion of the jaw 36 and also the movable section 64 thereof as shown in Fig. 3. These forwardly projecting side portions of the lever member 86 forming the bifurcation are indicated at 88-88. They are cut away adjacent to the inclined edges 72 on opposite sides of the part 64 to prevent engagement therewith. Extending transversely through the upper portion of the body 36 is a pivot pin 90 which projects beyond the outer sides thereof and enters the side sections 88-88 of the lever member, pivotally securing the same to the jaw body and serving as a fulcrum therefor. The pin 90 is preferably fixed to the lever member against rotation relative thereto by the provision of a screw member 92 (shown in Fig. 4) which projects through one of the side sections 88 thereof and bears against a flattened portion of the pivot pin. Extending through the rearward portion of the lever member 86 at an inclination thereto is an externally threaded control mem-

ber 94. The lever member is provided with an inclined internally threaded bore for receiving this member 94, as shown in Fig. 1. The control member 94 is provided with a head portion 96 on the outer end thereof, through which a handle 98 transversely extends. The handle is slidably movable through the head 96 but is frictionally held in any adjusted position by the provision of the coil spring 100 mounted in the member 94 in the manner shown in Fig. 1.

Immediately below the rearwardly projecting portion of the lever member 86 is a transversely extending bar 102 which is mounted for vertical movement. This bar is provided on the bottom face thereof with rearwardly inclined teeth 103 which are adapted to engage the teeth of the rack plate 80. The bar 102 has a lateral dimension greater than the rack plate 80 and the opposite ends thereof are mounted upon vertically extending stud members 104. The latter project downwardly into the widened base portion of the jaw 36 as shown in Fig. 2 and slidably fit vertical holes formed therein for this purpose. Encircling each stud 104 is a coil spring 106 which is seated at its lower end upon the widened base portion of the jaw 36 and at its upper end upon the bar 102. These springs yieldingly urge the bar 102 upwardly in a direction to disengage the teeth 103 thereof from the rack plate 80. It is evident that upon threaded advancement of the control member 34 it will engage and depress the bar 102 into engagement with the rack plate 80.

Preferably from the point of view of economy of manufacture it is desirable to form the control member 94 of relatively soft inexpensive metal and provide on the lower end thereof a hardened metal contact with the bar 102. This is preferably accomplished by forming a circular recess 108 in the bottom end of the control member 94 and mounting therein a hardened steel ball 100 which projects from the lower end of the control member. This ball is preferably locked in position by means of a washer 112 which encircles the lower end of the control member and which, when forced into position, inwardly turns the outer edges of the recess 108 so as to gripingly retain the ball in place. The washer 112 projects beyond the threaded portion of the control member 94 for abutment with the underside of the lever member 86 to serve as a stop limiting the withdrawal movement of the control member. The bar 102 is preferably provided on its outer surface with an insert or button 114 of hardened steel material which is disposed in position for engagement by the ball 100 of the control member. It is evident that upon rotation of the handle 98 in the direction to move the control member 94 downwardly the ball 100 will engage the button 114 and by this medium depress the rack bar 102 into engagement with the rack plate 80.

The upper end portions of the side sections 88-88 of the lever member 86 are shaped to extend past the rear sides of the projecting portion of the part 64 of the movable jaw structure. These sections of the lever member are shaped in a novel manner for urging the part 64 forwardly relative to the main body portion 36 of the jaw structure. This is preferably accomplished by the provision of two correspondingly shaped pins 116-116 which are disposed between the laterally projecting forward portion of the part 64 and the upper end of the side sections 88-88 of the lever member. The pins are received in 75 recesses formed in these members as shown in

Fig. 2 in order to retain the pins in position at all times. Referring to Fig. 2 the forward end of each pin is received in a recess 118 formed in the projecting side portion of the part 64 with which it is associated. The rear end of each pin 118 is received in a recess 120 in the upper end of the side section 88 of the lever member with which it is associated.

The operation of the lever member 86 is shown by a comparison of Figs. 1 and 2. In Fig. 1 the control member has been retracted so that the rack bar 102 is disengaged from the rack plate 80. Upon rotation of the handle 98 to advance the control member 94 downwardly the ball 110 will engage the button 114 of the rack bar and depress the latter into engagement with the rack plate. This will lock the main part 36 of the movable jaw structure against further translational movement on the body 38. Upon further rotation of the handle 98 in the same direction the lever member will travel up the threads of the control member and will rock in a counterclockwise direction about the axis of the pivot pin 90 and assume for its final position that shown in Fig. 2. During this rocking movement of the lever member 86 the side sections 88-88 thereof will force the pins 116-116 forwardly and thereby advance the part 64 of the jaw structure toward the face plate 58 of the fixed jaw 34. This movement of the jaw part 64 will compress the spring 76. When the handle 98 of the control member 94 is rotated in the opposite direction to withdraw the same, the lever member 86 will travel down the threads of the control member and rock in a clockwise direction thereby enabling the compression spring 76 to move the jaw 64 rearwardly. This will separate the face plates 58 and 60 and enable the object gripped therebetween to be removed. Upon further turning of the handle 98 in a withdrawing direction the pressure on the rack bar 102 will be relieved thereby enabling the coil springs 106 to raise the rack bar out of engagement with the teeth of the rack plate 88. The parts will then assume the position shown in Fig. 1 thereby enabling the movable jaw structure to move back and forth on the body 38.

An adjustable stop is provided on the lever member 86 which limits its clockwise movement. This stop is in the form of a vertical bolt 122 located in the tail portion of the lever member 86 as shown in Fig. 1 and arranged to depend below the same for engagement with the rearwardly projecting portion of the jaw 36. The bolt is adjustably secured in the lever member by a nut 124 threaded to the lower projecting end thereof. Upon adjustment of the nut it is possible to regulate the distance the bolt 122 projects below the lever member. Upon engagement of the bolt with the jaw 36, further retractable movement of the control member will fail to effect further swinging movement of the lever member 86 but thereafter it will itself be raised relative to the lever member and the body 38 enabling the rack bar 102 to release its clutching engagement with the rack plate.

To protect the rear end section of the elongated supporting body 38, and particularly the rack plate 80 thereof, a removable cover member 125 is provided. The cover member is of channel formation and of a size to embrace the upper portion of the rear end section of the body 38. To removably secure the cover member in place on the body, the cover is provided with two or more spaced apart recesses 126 on each side

thereof in the manner shown in Fig. 4. These recesses cooperate with jutting elements on the body 38 in the form of projecting screws 128. When the cover member is properly positioned on the body, the screws are received fully within the recesses. The upper surface of the cover adjacent to the rack bar 102 is cut away to allow the ball end of the control member to directly engage the rack bar as shown in Fig. 2. To prevent the jaw body 36 from completely sliding off of the rear end of the elongated body 38 a stop is provided on that end in the form of the transversely extending plate 130 secured thereto by screws 132. The stop plate extends latterly across the open ends of the guiding grooves 40 and forms an abutment thereat against which the body 36 will strike. The stop plate is detachable to allow removal of the jaw structure 36 and associated parts from the elongated body 38.

It is preferred to make the teeth of the rack plate 80 and the rack bar 102 relatively fine and closely related. A tooth spacing of $\frac{1}{16}$ of an inch is desirable on both of these elements.

As a result of the operating connections formed by the pins 116, the rocking motion of the lever member 86 is converted into a straight line motion advancing the jaw member 64 and its associated face plate 60 in continuous parallel relation to the fixed jaw 34 and its face plate 58. Preferably the clamping plates are formed of tool steel. At all times the gripping surfaces of the face plates 58 and 60 are maintained in parallel relation to one another. If the pins 116 were omitted and the lever member 86 allowed to directly engage the jaw part 64, a wiping or camming action would occur which would cause the engaging surfaces to wear and affect the rapidity of the operation. The location of the pivoting axis of the lever member adjacent to the pins 116 and thereby spaced from the control member 94 as shown in Fig. 2, serves to multiply the force exerted by the control member. The yielding force exerted by the coiled spring 76 urges the jaw member 64 rearwardly at all times and continuously maintains the pins 116 in contact with the closed ends of the recesses 118 and 120 in which they are mounted. The resistance of the spring 76 is greater than the resistance of the two springs 106 tending to lift the rack bar 102. As a result, the downwardly threaded advancement of the control member will first depress the rack bar into engagement with the rack plate and thereafter upon further rotation in the same direction, cause the lever member to travel up the threads of the control member and rock in the direction to thrust the jaw 64 toward the fixed jaw 34.

The bifurcated end sections 88 of the lever member apply an equal pressure on the opposite side portions of the removable jaw 64. The application of equal pressures on the opposite ends rather than on the middle portion of the jaw part 64, assures an equal distribution of gripping pressure by the face plate 60 regardless of any irregularity in the form of the object disposed between the jaws. Otherwise, if pressure were exerted at the middle portion of jaw part 64, it would tend to twist latterly as it worked on an irregular object, and possibly bind in the guiding grooves of the slide 66. It is to be noted that the face plate 60 overlies the front end of the slide 66 and serves as a stop limiting rearward traveling of the jaw member 64 in the direction urged by the spring 76.

The upward rearward inclination of the control member 94 and the bore of the lever member in which it is received predisposes the handle 98 further to the rear of the face than if the control member extended vertically or directly up and down. This removes the handle away from the working area of the jaws allowing the operator more freedom to perform his work. The slideable mounting of the handle 98 in the head 96 of the control member enables the handle to be shifted either one way or the other way to remove it further from the work and also to provide greater leverage when the control member is rotated.

As a result of this invention, it is seen that a single screw member performs two operations, namely, to lock the movable body 36 to the elongated supporting body 38, and thereafter to force the movable jaw part 64 forwardly under great pressure toward the fixed jaw. After the jaw body 36 has been manually adjusted to a position where the clamping plates 48 and 60 lightly grip and hold an object therebetween, usually it is only necessary to rotate the handle one and one-half times to both lock the two bodies 36 and 38 together and to clamp the object under extremely high pressure. At the most, three turns of the handle will be required to perform this dual operation. The vise illustrated herein has approximately one-third more capacity than conventional vises of the same size.

While I have illustrated and described the improvements of the present invention in a preferred form of a vise, it will be understood that various changes and modifications therein may be made by those skilled in the art without departing from the spirit and scope of my invention. For example, while I have shown a vise adapted to be used on a bench it will be evident that my improvements may equally advantageously be incorporated into a vise for use on drill presses, milling machines and other types of apparatus. It will therefore be understood that the claims appended hereto are intended to cover all changes and modifications which fully come within the true spirit and scope of my invention.

What I claim is:

1. In a vise, a normally stationary body having a fixed jaw, a second body slidably mounted on the first body for translational movement toward and away from the fixed jaw and capable of being locked in adjusted position, a movable jaw mounted on said second body in opposed relationship to the fixed jaw and for straight line movement relative to the second body toward and away from the fixed jaw, a lever pivotally connected to said second body for swinging movement about an axis extending transversely to the respective paths of movement of the second body and the movable jaw and provided with a part disposed on the side of said movable jaw opposite to the fixed jaw, and an element interposed between the movable jaw and said part of the lever and bearing thereagainst so that the element is capable of rocking movement relative to the movable jaw and said part of the lever as it converts the angular movement of the lever to the straight line motion of the movable jaw.

2. In a vise, a normally stationary elongated body having a fixed jaw at one end thereof, a second body mounted on the first body for slideable movement toward and away from the fixed jaw and capable of being locked in adjusted posi-

tion, a movable jaw opposing the fixed jaw and mounted on said second body for straight line motion relative thereto toward and away from the fixed jaw, a lever pivotally connected to said second body about an axis extending transversely to the respective paths of movement of the second body and the movable jaw and having a part disposed on the side of said movable jaw opposite to the fixed jaw, and a pin having one end pivotally engaging said part and the opposite end pivotally engaging said movable jaw and operatively coupling the part to the jaw for moving the latter toward the fixed jaw when the lever is swung in one direction, said pin converting the angular motion of the lever to the straight line motion of the movable jaw and rocking on its ends while accomplishing such action.

3. In a vise, a normally stationary elongated body having a fixed jaw at one end, a second body slidably mounted on the first body for movement toward and away from the fixed jaw, means for locking the second body to the first body against movement away from the fixed jaw, a movable jaw opposing the fixed jaw and mounted on the second body for straight line motion toward and away from the fixed jaw, a lever having one section thereof bifurcated so as to straddle the second body, means pivotally mounting the lever on the second body for swinging movement about an axis extending transversely to the paths of movement of the second body and the movable jaw in such a manner as to dispose the bifurcated section of the lever immediately adjacent to the movable jaw and on the side thereof opposite to the fixed jaw, and a pin interposed between each side of the bifurcated section of the lever and the movable jaw and transmitting the force exerted by the swinging movement of the lever in one direction to the movable jaw to advance the same toward the fixed jaw, spring means yielding resisting said advancing movement of the movable jaw toward the fixed jaw, each of said pins having its respective ends pivotally bearing on the movable jaw and on the bifurcated section of the lever and rocking on said bearing points as they convert the angular motion of the lever to the straight line motion of the movable jaw.

4. A vise comprising, in combination, an elongated body supporting an upright fixed jaw member adjacent to one end thereof, a second body slidably mounted on said first body for longitudinal movement toward and away from the fixed jaw member, a movable jaw member slidably mounted on said second body for longitudinal movement toward and away from the fixed jaw member; a lever pivotally connected to said second body for swinging movement about an axis extending transversely to said first body, and upon swinging movement in one direction, operatively engaging said second jaw member and advancing the same relative to the second body and toward said fixed jaw member; an elongated rack plate carried by said first body, a rack bar carried by said second body and mounted for movement relatively thereto into and out of engagement with the teeth of said rack plate respectively to lock or unlock the second body against slideable movement, said lever having an internally threaded bore opening out on opposite sides thereof; and a control member extending through said bore of the lever and being externally threaded for threaded engagement with the bore, said control member, upon threaded advancement in one direction moving

11

said rack bar into engagement with the teeth of the rack plate and thereafter, upon further threaded advancement, swinging the lever in the direction to advance the second jaw member toward the fixed jaw member.

5. A vise comprising, in combination, an elongated body supporting an upright fixed jaw member adjacent to one end thereof, a second body slidably mounted on said first body for longitudinal movement toward and away from the fixed jaw member, a movable jaw member slidably mounted on said second body for longitudinal movement toward and away from the fixed jaw member; a lever pivotally connected to said second body for swinging movement about an axis extending transversely to said first body, and upon swinging movement in one direction operatively engaging said second jaw member and advancing the same relative to the second body and toward said fixed jaw member; an elongated rack plate carried by said first body, a rack bar carried by said second body and mounted for movement relatively thereto into and out of engagement with the teeth of said rack plate respectively to lock and unlock the second body against slidable movement, said lever having an internally threaded bore extending therethrough from one side to the other side thereof; a control member of greater length than said bore extending therethrough and projecting from the opposite ends thereof, said control member being externally threaded for threaded engagement with the threads of said bore and having a handle on one projecting end thereof for turning the same and having means on the other projecting end for engaging said rack bar, and said handle, upon rotation in one direction threadedly advancing the control member in said bore and causing the opposite end of the control member to move the rack bar into clutching engagement with the teeth of the rack plate and thereafter, upon further rotation in the same direction, causing the lever to threadedly advance relative to the control member and thereby to swing in the direction to advance the second jaw member toward said fixed jaw member.

6. In a vise, a normally horizontally extending elongated body, an upright jaw member fixed to the forward end of said body and having the object gripping surface thereof facing rearwardly thereof, a second body, means slidably mounting said second body on the elongated body for uninterrupted slidable movement longitudinally therewith, a second jaw member, means slid-

12

ably mounting said second jaw member on said second body for longitudinal movement paralleling the path of the slidable movement of the second body and having its object gripping surface facing forwardly in opposed relation to the corresponding gripping surface of said fixed jaw member, a lever having one end section thereof bifurcated so as to straddle the second body, means pivotally connecting the lever to the second body for swinging movement about a transversely extending horizontal axis in such a manner as to dispose the bifurcated end section thereof immediately adjacent to said second jaw member, means operatively coupling the bifurcated end section of the lever to the second jaw member so that upon rocking movement of the former in one direction it will move the second jaw member forwardly toward the fixed jaw member, an elongated rack plate fixed to the upper surface of said elongated body and extending longitudinally thereof, a rack bar carried by said second body and depressibly engageable with the rack plate to lock the second body against slidable movement, said lever having an upwardly rearwardly inclined internally threaded bore opening out through the top and bottom sides thereof, a control member of greater length than said bore extending therethrough and projecting from the opposite ends thereof, said control member being externally threaded for threaded engagement with said bore and provided with a handle on the upper end thereof and a rounded surface on the lower end of said control member engageable with said rack bar.

BURTON H. PARKER.
